JUVENILE CAR SEAT

Joseph C. Hafner, 1321 Rudy Drive, Troy, Ohio 45373,
and Raymond J. Callebaut, 30 Dawson Drive, Need-
ham, Mass. 02192

Filed Oct. 25, 1974, Ser. No. 518,165

Term of patent 14 years

Int. Cl. D6—01

U.S. Cl. D6—7

FIG. 1

—FIG. 2

FIG. 3

FIG. 4

FIG. 5

FIG. 1 is a view in front elevation of a juvenile car seat showing our invention;

FIG. 2 is a side view of the car seat of this invention;

FIG. 3 is a back view of the car seat of this invention;

FIG. 4 is a top plan view of the car seat of this invention; and

FIG. 5 is a bottom view of the car seat of this invention.

The side of the seat not shown is a mirror image of the side shown.

We claim:

The ornamental design for a juvenile car seat, as shown and described.
